UNITED STATES PATENT OFFICE.

NEAL H. STEVENS, OF KATALLA, TERRITORY OF ALASKA.

CIGARETTE HOLDER AND MOUTHPIECE.

1,374,686.

Specification of Letters Patent.

Patented Apr. 12, 1921.

Application filed May 21, 1920. Serial No. 383,220.

To all whom it may concern:

Be it known that I, NEAL H. STEVENS, a citizen of the United States, residing in the city of Katalla, Territory of Alaska, have 5 invented new and useful Improvements in Cigarette Holders and Mouthpieces, of which the following is a specification, reference being had to the accompanying drawings.

10 The present invention pertains to a combined cigarette holder and mouthpiece, and the primary object is to provide a simple and efficient device of this nature, for the use of cigarette smokers who roll their own 15 cigarettes, wherein is combined the advantages of a cigarette mouthpiece and holder, adapted to facilitate the rolling of the cigarette.

In the drawings:

20 Figure 1 is a perspective view showing the device with a cigarette paper locked at the end thereof in the process of making a cigarette.

25 Fig. 2 is a similar view showing the cigarette completed.

Fig. 3 is a perspective detail showing the inner end of the device in full and with the paper holding clamp and ring released.

In the construction as shown in the drawings, the device consists of an ordinary 30 mouthpiece or stem 1 provided with the ordinary longitudinal vent 2 and having the forward or cigarette engaging end cut down so as to leave an annular shoulder 3. Upon 35 this same end is pivotally mounted the paper clamp 4, same being secured to the stem 1 by having its inner end in pivotal engagement with the ring 5 permanently set over the end of the stem 1. The outer end of 40 this clamp 4 carries two oppositely disposed paper engaging ears 6 which are bent sidewise toward the axis of the stem 1, and thus adapted to frictionally engage the forward end of the stem 1. An auxiliary paper 45 locking ring 7 is provided and slidingly mounted over the stem 1 and adapted to slide down over and upon the end of the cigarette when formed, as shown in Fig. 2, so as to lock the paper in form when the 50 cigarette is completed. The ring 7 is anchored to the stem 1 by means of a short chain 8 so as to prevent its loss.

In operation, in forming the cigarette the cigarette paper 9 is clamped endwise at the 55 forward end of the stem, as shown in Fig. 1. This is accomplished by pressing the paper holding clamp 4 down over the end

of the paper so that the paper is frictionally held between the end of the stem and the clamp 4. The usual portion of tobacco is 60 then deposited upon the paper 9, after which the cigarette is rolled and formed in usual manner. The ring 7 is then slid down over the end of the cigarette so formed, thus locking the completed cigarette in permanent 65 form.

While I have herein described a certain specific method of constructing and assembling the elements of my invention, it is understood same may be varied in minor 70 details, not departing from the spirit of my invention as defined in the appended claims.

What I claim to be new and patentable is:

1. A cigarette holder and mouthpiece comprising a stem with a longitudinal vent 75 therethrough; a paper engaging clamp pivotally mounted at the forward end of the stem; a paper engaging ring slidingly mounted over the forward end of the stem; and means for permanently retaining said 80 paper engaging ring upon the stem.

2. A cigarette holder and mouthpiece comprising a stem with a longitudinal vent therethrough; and a paper engaging clamp pivotally mounted at the forward end of 85 the stem.

3. A cigarette holder and mouthpiece comprising a stem with a longitudinal vent therethrough, the forward end of the stem being cut down so as to leave an annular 90 shoulder; means for releasably securing the cigarette paper to the forward end of the stem; and a paper engaging ring slidingly mounted over the forward end of the stem.

4. A cigarette holder and mouthpiece 95 comprising a stem with a longitudinal vent therethrough, the forward end of the stem being cut down so as to leave an annular shoulder; means for releasably securing the cigarette paper to the forward end of the 100 stem; a paper engaging ring slidingly mounted over the forward end of the stem; and means for permanently retaining said paper engaging ring upon the stem.

5. A cigarette holder and mouthpiece 105 comprising a stem with a longitudinal vent therethrough; and a paper engaging ring slidingly mounted over the forward end of the stem.

NEAL H. STEVENS.
